UNITED STATES PATENT OFFICE

WILLIAM ROSE, OF GAINSBOROUGH, ENGLAND.

APPARATUS FOR FILLING BAGS OR CONTAINERS WITH TEA, TOBACCO, AND OTHER LIKE SUBSTANCES.

1,114,529.

Specification of Letters Patent. Patented Oct. 20, 1914.

Application filed May 5, 1914. Serial No. 836,507.

To all whom it may concern:

Be it known that I, WILLIAM ROSE, a subject of the King of Great Britain, residing at Albion Works, Gainsborough, England, have invented new and useful Improvements in or Relating to Apparatus for Filling Bags or Containers with Tea, Tobacco, and other like Substances, of which the following is a specification.

This invention relates to apparatus for filling bags, or containers, with tea, tobacco and other like substances, the said apparatus being of the kind in which the bags, or containers, to be filled are placed in recesses, or boxes and this invention has for its object to provide means whereby bags, or containers, which have not been properly charged are removed from their recesses, or boxes, which removal can be effected without crushing, or otherwise injuriously affecting the bag, or container, and the invention mainly consists in providing a reciprocating and oscillating carrier, having a plunger and a gripping device, which are adapted to operate to cause a bag, or container, which has not been properly charged to be gripped and removed from its recess, or box.

I will describe this invention with reference to the accompanying drawings which illustrate the best means with which I am acquainted for carrying it into effect.

Figures 1 and 2 show in elevations, with parts in section, a device in accordance with this invention for removing bags, or containers, which have not been properly charged, Fig. 1 showing the position of the parts when the bag, or container, has been properly charged, and Fig. 2 showing the position of the parts when the said bag, or container has not been properly charged. Fig. 3 shows in elevation, drawn to a smaller scale than Figs. 1 and 2, the device shown in the said Figs. 1 and 2 and the means for operating it. Fig. 4 is a similar view to Fig. 3 but showing parts in a different position. Fig. 5 is an elevation at right angles to Fig. 4. Fig. 6 is a horizontal section taken on the line A. B. Fig. 4. Fig. 7 is an elevation of parts shown in Figs. 3 and 4 but with parts in different positions to those shown in the said Figs. 3 and 4. Fig. 8 is a similar view to Figs. 3 and 4 but showing parts in positions different from those shown in the said Figs. 3 and 4. The aforesaid Figs. 3, 4, 7

and 8 show in progressive stages the position of the parts for effecting the removal of an empty bag, or container, from its recess, or box.

According to this invention I provide apparatus for filling bags, or containers, with a reciprocating and oscillating carrier 1 (see more particularly Figs. 1 and 2) carrying a plunger 2 and a finger 3, constituting the movable member of a gripping device, the other member of which device is constituted by a projection, or stop, 4, (hereinafter referred to as the fixed member) on the said plunger 2.

The plunger 2 has a stem 5, slideable in the carrier 1, provided with a collar 6 upon which bears a coiled spring 7 which acts to yieldably hold the plunger 2 in its normal position beyond the lower end of the carrier 1 as shown in Fig. 2. Outward movement of the plunger 2 is limited by the collar 6 engaging with a part 8 of the carrier 1.

The finger 3, constituting the movable member of the gripping device, is pivotally mounted, at 9, on the carrier 1 and is normally held in its closed, or gripping, position by a spring 10 connected at one end to the carrier 1 and at its other end to an arm 11 secured to, or formed in one with, the said finger 3, the movement of the finger, 3 under the action of the spring 10, being limited by a stop 12, on the said finger, engaging with a stop 13 on the carrier 1. The finger 3 is caused to open at the proper times, by an arm 14 secured to, or formed in one with, the said finger, which arm is operated by means hereinafter described.

The carrier 1 is so arranged that when the recesses, or boxes, 15, into which the bags, or containers 16, to be filled are placed, are at rest the plunger 2 on the said carrier is in alignment with the open end of one of the said recesses, or boxes, containing a bag, or container 16, (which bag, or container is, or should be, at this stage, properly charged and it is presumed for the moment that it is properly charged) so that when the carrier 1 is caused to descend the said plunger will enter the open end of the said bag, or container, and descend therein until it meets the contents which arrests any further entry. The carrier 1, however, continues to descend until the finger 3 (which at this stage has been moved to its open position) is brought

into a position, outside the bag, or container, to grip the upper part of one of the sides thereof, but owing to the relative movement of the said carrier with respect to the plunger 2 the active parts of the gripping members 3 and 4 are moved out of line with each other so that when the finger 3 is moved to its closed position, as shown in Fig. 1, it fails to grip the said side of the bag, or container, between it and the fixed member 4 and upon the return or ascending movement, of the carrier 1, the properly filled bag, or container, is left in its recess, or box 15. If, however, the charging of the bag, or container, 16, has from any cause not been properly effected no arrest of the descending movement of the plunger 2 would be effected and consequently the active parts of the gripping members 3 and 4 remain in line with each other, as shown in Figs. 2 and 3 so that when the finger 3 is moved to its closed position as shown in Fig. 4, it grips the upper part of one of the sides of the bag, or container, between it and the fixed member 4 and upon the return, or ascending movement, of the carrier 1 the empty bag, or container, is withdrawn from its recess, or box, 15 as shown in Fig. 7. The carrier 1 is then turned on its pivot 17 and the movable finger 3 is operated to release the bag, or container 16, as shown in Fig. 8, which then falls clear away of the apparatus.

The carrier 1 may be caused to reciprocate by any suitable means, for example, it may be fixed to, or connected with, any suitable reciprocating part of the apparatus. In Figs. 3, 4, 5, 6, 7 and 8 I have shown this as being effected by a piece 18 slideable on a rod 19, to which piece 18 the carrier 1 is connected by the pivot pin 17. The sliding piece 18 is operated, through a connecting rod 20, by a crank 21 secured to a rotating shaft 22.

The oscillation of the carrier 1 may be effected, as shown by way of example in the accompanying drawings, by an arm 23, formed in one with, or secured to, the carrier 1, the free end of which engages, through an anti-friction roller 24, with a cam-groove 25 formed in a piece 26 secured to the framing 27 of the apparatus.

The finger 3 is moved to its open position to permit of the upper part of the bag, or container, 16, passing between it and its fixed member 4, by an arm 28 of a bell-crank lever which is caused, by a spring 29, to act, through an anti-friction roller 30, on the arm 14 on the said finger, as shown in Fig. 3; a cam 31, secured to the shaft 22, acts, through an anti-friction roller 32 on the other arm 33 of the said bell-crank lever, to release the arm 14, as shown in Fig. 4, thereby permitting the finger, under the action of its spring 10, to return to its closed position. 65 As the carrier 1 approaches the end of its

upward movement the finger 3 is caused to open by the tail of the suitably shaped arm 14 engaging with a stationary projection, such, for example, as a roller 34 secured to the cam-piece 26, so that any bag, or container, held by the said finger 3 and the fixed member 4 is thereby released, as shown in Fig. 8.

It is to be understood that the invention is not restricted to the precise details of construction hereinbefore described and shown in the accompanying drawings, as it is obvious that modifications may be made without departing from the nature of the said invention.

What I claim is:—

1. In apparatus for filling containers, a plunger adapted to rest upon the charged material in the container, gripping means for engaging and lifting the container and means controlled by the position of the plunger for rendering the said gripping means inoperative.

2. In apparatus for filling containers, a plunger adapted to rest upon the charged material in the container, gripping means having coöperating parts which register in gripping position to engage and lift the container, and means for holding said parts out of register when the plunger is in predetermined position on the charged material.

3. In apparatus for filling containers, a plunger adapted to rest upon the charged material in the container, gripping means having coöperating parts normally in register to grip and lift the container, and means for relatively displacing said parts out of register when the said plunger rests upon a full charge in the container.

4. In apparatus for filling containers, a plunger adapted to rest upon the charged material in the container, gripping means for engaging and lifting the container, said means comprising a gripper jaw and a co-operating abutment with which said jaw is normally in register, and means for relatively displacing out of register said jaw and abutment when the said plunger rests upon a full charge in the container.

5. In apparatus for filling containers, a plunger adapted to rest upon the charged material in the container, gripping means having coöperating parts which register in gripping position to engage and lift the container, a displaceable support for one of said parts and means for automatically displacing said support when the plunger is in predetermined position on the charge in the container.

6. In apparatus for filling containers, a reciprocating carrier, a plunger thereon adapted to enter a container and rest upon the material charged therein, a gripping device for engaging the container, means for rendering said gripping device operative

only in predetermined position of the plunger, and means operative on the return movement of the carrier for freeing the container from the gripping device.

- 5 7. In apparatus for filling containers, a reciprocating carrier, a plunger thereon adapted to enter a container and rest upon the material charged therein, a gripping device for engaging the container, means for 10 rendering said gripping device operative only in predetermined position of the plunger, and means engaging said gripping device to open the same on the return movement of the carrier.
- 15 8. In apparatus for filling containers, a reciprocating carrier, a displaceable plunger thereon adapted to enter a container and rest upon the material charged therein, a gripping device on the carrier adapted to grip 20 the container and remove the same on the return movement of the carrier, said gripping device comprising registering elements one of which is subject to the movement of the plunger with relation to the carrier, 25 whereby said coöperating gripper elements may be relatively displaced out of register.
9. In apparatus for filling containers, a reciprocating carrier, having a relatively displaceable plunger adapted to enter a container and rest upon the material charged 30 therein, a gripping device on said carrier adapted to engage and lift the container, said gripping device comprising a pivoted jaw and a coöperating abutment element, an operative connection between said abutment 35 element and the plunger for displacing said abutment out of register with the jaw member and means at the opposite ends of the 40 stroke of the carrier to engage and tempo-

rarily open said pivoted jaw, for the purpose described.

10. In apparatus for filling containers, a reciprocating pivoted carrier, a plunger thereon adapted to rest upon the material charged into a container, a gripping device 45 to engage the container and operative in predetermined position of the plunger, and means for tilting said carrier at one end of its reciprocating stroke and simultaneously opening said gripper to discharge a gripped 50 container.

11. In apparatus for filling containers, a movable carrier for removing insufficiently filled containers, said carrier comprising a gripping device having coöperating gripping 55 elements, one of said elements being pivotally mounted on the carrier and the other element being longitudinally displaceable thereon, for the purpose described.

12. In apparatus for filling containers, a reciprocating carrier, a gripping device mounted thereon, comprising coöperating elements lying in register in gripping position, means engaging the charge in the container, to displace one of said elements out 60 of registering position when a properly charged container is engaged, and means for rocking the other gripping element to open 65 the same temporarily at the opposite ends of the stroke of the carrier, substantially as 70 described.

In testimony whereof I have signed my name to this specification in the presence of two subscribing witnesses.

WILLIAM ROSE.
